COMBINATION NECKTIE, POCKET HANDKER-
CHIEF, CUFF LINKS AND TIE TACK DISPLAY
AND MERCHANDISING UNIT

Isadore Nemeroff, Chicago, Ill., assignor to Carter &
Holmes, a corporation of Illinois

Application July 22, 1957, Serial No. 47,031

Term of patent 14 years

(Cl. D80—5)

I claim:

The ornamental design for a combination necktie, pocket handkerchief, cuff links and tie tack display and merchandising unit, substantially as shown.
